CLAIM

The ornamental design for a record album holder, as shown and described.

DESCRIPTION

FIG. 1 is a reduced perspective view of a record album holder showing our new design;

FIG. 2 is an end elevational view taken from the left of FIG. 1, shown at a 90° angle;

FIG. 3 is a top plan view thereof;

FIG. 4 is an end elevational view taken from the right of FIG. 1, shown at a 90° angle;

FIG. 5 is a bottom plan view thereof;

FIG. 6 is a front elevational view thereof; and

FIG. 7 is a rear elevational view.
